UNITED STATES PATENT OFFICE.

WOLFGANG E. SCHWARZMANN, OF SPRINGFIELD, MASSACHUSETTS, ASSIGNOR TO
AMERICAN BOSCH MAGNETO COMPANY, OF SPRINGFIELD, MASSACHUSETTS, A
CORPORATION OF NEW YORK.

MAGNETO FOR MULTICYLINDER ENGINES.

1,402,897.

Specification of Letters Patent. Patented Jan. 10, 1922.

Application filed March 27, 1919. Serial No. 285,449.

To all whom it may concern:

Be it known that I, WOLFGANG E. SCHWARZMANN, a citizen of the United States, residing at Long Meadow, Springfield, in the county of Hampden, State of Massachusetts, have invented certain new and useful Improvements in Magnetos for Multicylinder Engines; and I do hereby declare the following to be a full, clear, and exact description of the invention, such as will enable others skilled in the art to which it appertains to make and use the same.

The present invention relates to magnetos for igniting the combustible mixture in multicylinder internal combustion engines, and particularly to magnetos of compact, self-contained and inexpensive though strong, efficient and accessible construction.

Heretofore, in magnetos having the shafts of the distributor and magneto inclined to each other, it was usual to mount the distributor of the magneto upon some detachable support or mounting at a comparatively remote location from the shaft of the generating rotor located within the magneto housing and to connect the distributor shaft with the rotor shaft by gears with a detachable gear housing having a bearing for supporting the portion of the rotor shaft carrying the driving gear. Inasmuch as the parts were remote and detachable, considerable machining and accurate fitting was necessitated, and the parts had to be comparatively large and expensive, aside from the general structure being cumbersome and intricate, in order to provide a sufficiently strong magneto. In such magnetos, also, the permanent magnets are located with the arms thereof disposed at right angles to the axis of the magneto rotor, further making the magneto structure large and cumbersome.

In accordance with one part of the invention, the magneto housing has a bearing for a rotor and integral wall portions forming a gear cavity adjacent the bearing so that the top wall portion of the cavity forms a base for the distributor and distributor block, as well as having a bearing therein for rotatably supporting the distributor shaft inclined to the axis of the rotor; the shaft carrying a distributor element in cooperation with the block and having gearing for driving the same from the rotor.

On account of the comparatively small

size of the worm gearing, and its location, 55 the distributor may be relatively small and inexpensive due to the small amount of high tension insulation required in the block and to the shortness of the high tension wire connecting the collector and distributor brushes. 60

Although the magnet of the magneto may extend perpendicularly of the axis of rotation of the rotor, I prefer to arrange the magnet with its arms lengthwise of the rotor, so that the distributor may be located 65 at the top or on one side face of the magneto and therefore entirely accessible. The magnet may be of the usual horse-shoe type, although I prefer to provide a separable magnet with a flat cross-bar detachably fastened to flat arms and providing a bearing for that end of the rotor and supporting the mechanical interrupter in an accessible position.

Whether or not the magnet is arched, the 75 non-magnetic housing for the magneto preferably has a flange extending around the worm gearing to provide a seat for a removable plate closing the gearing to the outside, and also providing a channel extending 80 from the bearing of the distributor shaft to a terminal portion receiving a grease cup.

In the accompanying drawings illustrating this preferred form of construction in application, as an example, to a high tension 85 wound armature type of bipolar magneto having a separable magnet with its arms extending lengthwise of the armature, and a distributor intended for a four-cylinder engine and located on the top of the magneto. 90

Fig. 1 is a longitudinal section of the magneto on line 1—1 of Fig. 2; Fig. 2 is a section on line 2—2 of Fig. 3; Fig. 3 is a section on line 3—3 of Fig. 4; and Fig. 4 is a view, partly broken away, from the top 95 of the magneto.

As disclosed in my copending application, Serial No. 278,176, filed February 20, 1919, the magneto has an armature 1 carrying primary and secondary generating windings 2 100 and rotatable in a ball bearing 3 at the driving or collector end of the magneto and a ball bearing 4 at the rear or interrupter end. The magnet is composed of two flat arms 5 extending lengthwise of the armature, and a separable flat cross-bar 6 carrying the bearing 4 and supporting the mechanical interrupter 7 outside in an accessible posi-

tion. The mechanical interrupter may be of the well known kind having rotatable interrupter elements, the insulated one of which is connected in the circuit of the primary winding and the condenser 8, whereas the other one is grounded on the frame of the magneto. The cam ring 9 carries the interrupter cams 10 and the timing arm 11, and the cover 12, held in place by the spring 13, carries the grounding brush 14 and the binding post 15.

The collector 16 is fastened on the driving shaft 17 inside the bearing 3 so as to be easily connected to the high tension terminal of the secondary winding. The brush holder 18 has a brush 19 cooperative with the collector. Outside the bearing 3, that is overhanging it, is a worm 20 fast on the driving shaft 17 and in mesh with a worm 21 forming worm gearing of one-half speed reduction between the armature and the vertical distributor shaft 22 on which the worm wheel is fastened. The rotatable element 23 is carried on the shaft 22 in cooperation with the four spark plug distributor segments 24 mounted in the distributor block 25 on the top of the magneto at the driving end thereof. From the segments, the conductors 26 lead to the respective spark plugs in the engine cylinders in the well known way.

An aluminum housing has cast in it the pole shoes 27 to which the magnet arms 25 are attached. Besides forming a closure for the armature between the arms of the magnet, it carries the bearing 3 and forms a closure for the collector 16. Also it carries the bearing 28 for the distributor shaft 22 and provides a channel 29 into the terminal portion of which fits a grease cup 30. At the top of this housing, opposite the base 31 thereof, is an integral distributor seat 32 for the distributor block 25. Furthermore, the housing has a cavity at 33 for the worm gearing with a seat for a detachable plate 34 which fits over the driving shaft 17 and closes the gearing to the outside in a manner permitting ready inspection and replacement thereof.

50 The outside conductor 35 connects the collector brush 19 with the binding post 36 which is connected through a central brush 37 to the rotatable element 23 of the distributor.

55 As a result of the fact that the aluminum housing carries the pole shoes 27 and the bearings 3 and 28, and forms closures for the armature, collector and worm gearing, besides a base for the distributor, the 60 machining and fitting required is considerably reduced, which, together with the fact that two bearings suffice for the armature, and a short outside conductor connects the collector and distributor brushes, renders 65 the magneto compact but accessible, and

light but strong, and self-contained but small, and inexpensive but efficient, as has been shown by manufacture and test.

Having thus described my invention, what I claim is:

70 1. In a magneto for multicylinder engines, a rotor, a rotor housing having a bearing and integral wall portions forming a gear cavity adjacent said bearing, said cavity having a top wall forming a distributor base, a distributor block seated on said base, a distributor element rotatable in cooperation with said block and having a shaft journaled in said bearing on an axis inclined to the axis of the rotor, and gearing for driving the distributor shaft from the rotor.

75 2. In a magneto for multicylinder engines, a rotor, a rotor housing having a bearing and integral wall portions forming a gear cavity adjacent said bearing, said cavity having a top wall portion forming a distributor base with a lubricating channel extending thereto, a distributor mounted on said top wall portion and having a shaft journaled therein on an axis inclined to the axis of the rotor, 80 gearing for driving the distributor shaft from the rotor, and a grease cup fitted in said channel.

85 3. In a magneto for multicylinder engines, the combination of a housing being open at both ends and having an integral transverse wall intermediate the ends thereof, thereby forming an armature chamber on one side of said wall and a gear cavity on the other side of said wall, a bearing in said wall, a permanent magnet composed of two side arms and a cross-bar detachably fastened therebetween, said cross-bar closing one end of said housing and chamber, a bearing in said cross-bar, a rotor having a shaft rotatably mounted in said bearings, said shaft having a free end extending into said gear cavity, said cavity having a top wall forming an integral portion of said housing, a distributor on said top wall having a shaft rotatably mounted in said top wall, said distributor shaft being operatively connected to said shaft within said cavity.

90 4. In a magneto for multicylinder engines, the combination of a housing having an integral transverse wall separating said housing into an armature chamber and a gear cavity, a bearing in said transverse wall, means for closing the open end of said chamber, a bearing in said closing means, a rotor having a shaft extending through said chamber and rotatably supported in said bearings, said shaft having a free end extending from said bearing in said wall into said gear cavity, a gear fixed to said shaft 95 end in said cavity, said cavity having a top wall forming an integral portion of said housing, a bearing in said top wall, a distributor shaft in said last mentioned bearing and inclined to said rotor shaft, a distributor 100

- rotor and segment on said distributor shaft above said top wall, a gear on said distributor shaft in operative engagement with said gear on said rotor shaft in said cavity, and 5 a distributor block detachably mounted upon said top wall.
5. In a magneto for multicylinder engines, a rotor, a rotor shaft, two bearings therefor, a distributor arranged at the driving end of 10 the magneto, worm gearing overhanging the bearing at the driving end for driving the distributor from the rotor, a rotor housing having an open sided cavity for the worm gearing, said cavity having a top wall portion 15 forming a distributor base and a removable plate fitted over the end of the rotor shaft and closing said cavity to the outside.
6. In a magneto for multicylinder engines, a rotatable armature, a generating winding 20 mounted thereon, a collector electrically connected to one terminal of the generating winding, a housing covering the armature and collector and having a bearing, a distributor mounted on said housing at the collector 25 end of the magneto and having a shaft journaled in said bearing on an axis inclined to the axis of the armature, gearing for driving the distributor shaft from the armature, a brush holder having a brush cooper-
- ating with the collector, and an outside conductor extending from the brush holder in electrical connection with the brush thereof to the distributor in cooperation with the rotatable element thereof. 30
7. In a magneto for multicylinder engines, 35 a rotatable armature, a generating winding mounted thereon, a magnet having its arms extending lengthwise of the armature and having a flat cross-bar containing a bearing for the armature, a mechanical interrupter 40 electrically connected to the generating winding and supported on the outside of the cross-bar, a collector electrically connected to the generating winding and mounted on the armature to the driving end of the magneto opposite the mechanical interrupter, a 45 housing forming a closure for the armature and collector, a distributor mounted on the housing at the driving end, and worm gearing mounted in a cavity of the housing and 50 overhanging the bearing at the driving end for driving the distributor from the armature, said housing having a bearing for the driving end of the armature and another bearing for the worm gearing. 55

In testimony whereof I affix my signature.

WOLFGANG E. SCHWARZMANN.
